[57] CLAIM

The ornamental design for a multi-compartment drum, as shown and described.

DESCRIPTION

FIG. 1 is a front perspective view of the multi-compartment drum according to this invention showing our new design therefor;

FIG. 2 is a top plan view of the multi-compartment drum shown in FIG. 1;

FIG. 3 is a bottom plan view of the multi-compartment drum shown in FIG. 1;

FIG. 4 is a front elevational view as taken along line 4—4 in FIG. 2, the rear elevational view is the same;

FIG. 5 is a left side elevational view taken along line 5—5 in FIG. 2, the right side elevational view is the same; and, FIG. 6 is an exploded perspective view of the multi-compartment drum according to this invention showing the respective matable compartments thereof separated in a clam-shell fashion.
